UNITED STATES PATENT OFFICE

156,631

BEACH AND LAWN UMBRELLA

Samuel B. Korman, Pittsburgh, Pa., assignor to Kool Vent Metal Awning Corporation of America, a corporation of Pennsylvania

Application July 11, 1947, Serial No. 140,219

Term of patent 14 years

(Cl. D88—3)

To all whom it may concern:

Be it known that I, Samuel B. Korman, a citizen of the United States, residing in Pittsburgh, in the county of Allegheny and State of Pennsylvania, have invented a new, original, and ornamental Design for Beach and Lawn Umbrella, of which the following is a specification, reference being had to the accompanying drawing, forming part thereof.

Figure 1 is a perspective view of a beach and lawn umbrella, embodying my new design with the top tilted toward one side.

Fig. 2 is a reverse view of the umbrella shown in Fig. 1, looking at the interior.

I claim:

The ornamental design for a beach and lawn umbrella, as shown.

SAMUEL B. KORMAN.
